ELECTRIC HORN OR OTHER ACOUSTIC SIGNAL PRODUCER

Max Greiner, Berlin-Charlottenburg, Germany

Application April 24, 1928, Serial No. 272,448, and
in Germany October 11, 1926

7 Claims. (Cl. 177—7)

My invention relates to electric horns for producing acoustic signals, and is primarily designed for use as an attachment for automobiles although it is applicable for other purposes.

5 One object of my invention is a horn producing a clear tone resembling that of a trumpet. Another object is to provide a horn which is very economical in consumption of electric energy and which is of extremely simple and reliable construction guaranteeing a long life and negligible wear. From another aspect my invention relates to a diaphragm which when properly mounted is subjected to a radial tension like a strained drum skin and is, therefore, particularly adapted 10 for use in instruments for producing acoustic effects.

Other objects and features of novelty will appear from the description hereinafter and will be pointed out in the claims.

20 In the accompanying drawings I have illustrated some embodiments of my invention.

Fig. 1 represents an elevation of an electric horn, partly in section along the line 1—1 of Fig. 2,

25 Fig. 2 is a section partly along the line 2—2 of Fig. 1,

Fig. 3 is a plan-view of the embodiment shown in Fig. 1, the cap being omitted,

Fig. 4 is a perspective showing of the diaphragm 30 in relaxed condition,

Fig. 5 illustrates a section along the line 5—5 of Fig. 4,

Fig. 6 is a circumferential section of the diaphragm shown in Fig. 4,

25 Fig. 7 is an axial section corresponding to that of Fig. 1 through a modified embodiment.

Referring to Figs. 1 and 2, 10 indicates a funnel for conducting and collecting the acoustic waves generated by an oscillating diaphragm 12 which 40 closes one end thereof. While the funnel may be of any desired shape, its interior is preferably unobstructed and free from any plates or other members which are capable of oscillating and causing a disturbance of the oscillations of the 45 air body contained in the funnel. In this respect the invention may be different from certain known constructions and, as a consequence, may result in a much clearer tone. To one rim of the funnel a cup-shaped flange 11 is attached in any suitable

50 manner and formed to accommodate the diaphragm 12. A ring 13 is imposed upon the diaphragm and connected with the flange 11, for instance by means of rivets 14, clamping the rim of the diaphragm 12 against the flange. A bail 15 55 is placed upon the ring 13 in vertical position, its

ends being fastened to said ring, preferably by means of some of the rivets 14, (see Fig. 3). Over the straight top section of the bail a U-shaped sheet-metal-piece 16 is slipped, which carries between its downwardly projecting arms an iron 60 core 17 which is fixed in place by means of rivets 18. The iron core is formed with two downwardly projecting ends 19 provided with electro-magnetic coils 20 which are thus positioned in register with a diameter line of the diaphragm. The whole 65 structure is covered by a cap 22 inserted in the upwardly projecting margin portion of the flange 11. In the centre of the cap a hole is provided through which a bolt 21 fixed to the bail 15 is projecting. A nut 23 screwed upon the bolt 21 serves 70 to keep the cap 22 in place. In the centre of the diaphragm 12 a hole is provided in which a vertical bolt or pin 24 is inserted. This pin has a collar 25 bearing against the upper surface of the diaphragm and carries at its ends a nut 26 screwed 75 against the lower surface of the diaphragm. In this manner a comparatively rigid connection between pin 24 and the diaphragm is provided which, however, cannot completely prevent a relative movement of the parts during the oscillation of 80 the diaphragm. In order to diminish the destructive effect of the resulting friction washers 27 of a different metal, for instance of bronze, are placed between the diaphragm 12 and the shoulder 25 or the nut 26, respectively. 85

The upwardly projecting end of the bolt 24 carries an armature 28 attached in any suitable manner. In the embodiment shown, the upper end of the bolt 24 is of smaller diameter and the armature 28 is provided with a hole to be slipped 90 over said end. Beneath the armature 28 two washers 29 are placed upon the bolt or pin 24 holding between them a spring-blade 30 which is thus rigidly connected with the bolt 24 in parallel relation to the diaphragm. The one end of this blade 95 30 is clamped between a bracket 32 and a clamping-plate 31 riveted thereto. The bracket 32 is carried by the ring 13 and secured thereto, for instance by some of the rivets 14.

From the foregoing description it will be apparent that the blade 30 is arranged to participate in any oscillation which the diaphragm may perform and that, consequently, it increases the force with which the diaphragm counter-acts any axial displacement of the pin 24. 100

Another spring-blade 33 which is in the embodiment shown is integral with the spring-blade 30 is attached to the pin 24, extending from the upper-end of the same parallel to the diaphragm. Its free end is weighted by means of two plates 110

34 riveted to the spring as shown in Fig. 1. A strip 35 of bronze is folded over the end of the spring 33 and its ends are clamped between the spring and the plates 34. The floating weight 34 and the spring blade are so dimensioned as to constitute an oscillating system having a natural frequency which is substantially lower than that of the oscillating system constituted by the diaphragm 12, the spring blade 30, the armature 28, the pin 24 and the parts rigidly connected therewith. In the embodiment shown, for instance, natural frequency of the auxiliary oscillating system formed by the floating weight and its spring amounts to about fifty oscillations per second, while the natural frequency of the main system amounts to about two hundred and fifty oscillations per second.

The electric circuit of the coils 20 diagrammatically indicated in Fig. 2 is controlled by an automatic interrupter operatively connected to the oscillating system constituted by the diaphragm 12 and its associated parts. The switch of the interrupter is mounted upon an arm 36 inwardly projecting from the ring 13. Separated and individually isolated by interposed insulating pieces 37 are arranged two contact springs 38 and 42 which are placed upon the arm 36 and attached thereto by means of screws 39. Contact studs 40 are provided on the freely projecting ends of these springs registering with each other so that a circuit from the battery A may be closed through the coils 20, provided that the spring button switch 41 is pressed down. The upper spring 38 projects into the path of the spring 33 and is so bent that it tends to assume a position which is higher than that illustrated in Figs. 1 and 2, and in which the contacts 40 are separated. Also, the spring 42 has the tendency to raise to a higher position than shown so that, upon an upward movement of the upper spring 38, it will follow the same until it abuts against a stop pin 43. This stop pin is adjustably screwed into the projecting end of a sheet-metal-arm 44' arranged in insulated position upon the insulating pieces 37 and projects through a hole provided in the spring 38 without contacting the latter. An abutment formed by a rivet 44 is secured to the spring 33 in register with the spring 38 for engaging the same. Suitable washers of insulating material are inserted between the spring 33 and the upper and lower head of the rivet 44 to insulate the latter.

In order to prevent an excessive oscillation of the system constituted by the floating weight 34 and its spring a damping device is provided for the same comprising an angular spring 45 attached to the ring 13 and bearing with its upright arm against the end of the spring with a slight pressure. The support for the electric horn is preferably resilient, and elastic so that the structure supporting the electro-magnet and the rim of the diaphragm is capable of oscillating in the same direction as does the oscillating system of the armature. In the embodiment shown the support is formed by two spring-blades 46 riveted to the lower surface of the flange 11 and connected to a bracket 47 by means of a bolt 48. The bracket 47 is fixed in the place where the horn is to be attached. Owing to this suspension the entire supporting structure is capable of oscillating in a direction parallel to the oscillation of the diaphragm 12.

While any suitable diaphragm may be used in connection with the afore-described construction I prefer a particular form embodying cer-

tain novel features which will be pointed out hereinafter with reference to Figs. 4 and 6 illustrating a diaphragm in relaxed condition.

The diaphragm consists of spring sheet metal, for instance of steel or of bronze. It comprises a central part 50 which is preferably smooth and free from any impressions or indentations and is surrounded by one or several circular ridges 51. The novel feature of the diaphragm consists in the particular shape which it assumes when it is in relaxed condition, i. e. having its rim not clamped between plane ring surfaces as is the case when properly mounted in the horn. In relaxed condition the diaphragm assumes a form in which any circumferential section, inclusive a section along the ridges 51 for instance, represents a wave line such as shown in Fig. 6. In the embodiment shown this wave line comprises two complete waves only, corresponding to the saddle shaped curvature of the diaphragm illustrated in Fig. 4.

In order to produce this curvature the ridges 51 are stamped in the ordinary way in a flat and plane circular piece of particularly hard spring sheet metal. In the course of the stamping process interior stresses are produced in the margin portions of the plate which cause the same when relieved to assume the peculiar shape. I have found that a satisfactory diaphragm such as illustrated may be produced from a plate of 4½" diameter and .008" thickness, the material being hardened Swedish steel. If ridges such as illustrated are impressed to a depth of .05" a shape such as shown will result. If deeper impressions are made a shape is obtained in which two complete waves.

In the same manner as a wave line is increased in length when it is stretched to a straight line, the circumferential zone of the diaphragm is lengthened when the rim of the latter is clamped between plane surfaces. An increase in length of the circumference results, of course, in an increase in diameter whereby the central part of the diaphragm is strained like a drum-skin. In this condition the diaphragm resists with a strong force any axial displacement of its center which is necessary for obtaining a high frequency and a clear tone, and thus constituting a floating weight. The force may be increased to a certain extent by action of the spring 30.

The operation of the electric horn is as follows: When the button switch 41 is pressed down while the various parts are at rest in the relative position shown in the drawings, the electromagnets 20 are energized and attract the armature 28. The spring 33, consequently, is raised and the free ends of the contact springs 38 and 42 partake in this movement until the lower spring 42 abuts against the stop pin 43 whereby the contact studs 40 are separated. Now the circuit previously established through the coils 20 is interrupted so that the latter are de-energized and no longer attract the armature 28. Owing to the force exerted upon the latter by the diaphragm and the spring 30 which have been bent, it is vehemently returned into the original position and, therefore, does not come to rest when reaching the same but owing to the inertia imparted by the combined action of the diaphragm and the spring 30 it continues its movement for some time until finally it is again returned. During a part of the return stroke towards the electromagnet the armature

is attracted and its speed is consequently increased, hence, also, its amplitude of oscillation. Owing to the special type of diaphragm as described hereinbefore which has the feature of a stiffness increasing with the amplitude of oscillation the frequency of oscillation too is rapidly growing during the first stages of starting. After a short time of this starting period the auxiliary oscillating system constituted by the 10 spring 33 and its weights 34 will be aided to pass through resonance by the main armature system due to the higher frequency of the latter which is impressed on the system 33, 34.

For easily overcoming this point of resonance 15 and avoiding excessive oscillation of the auxiliary system a damping device 45 is provided.

After passing through resonance the stiffness of the system 33, 34 adds to that of the armature system so that the latter reaches a final frequency which is higher than it would be due to the stiffness of the diaphragm 12 and spring 30 alone.

While in the embodiment shown the armature 28 with the pin 24 forms the mass of the oscillating system, any other mass or weight could be used provided that other suitable means for imparting the oscillation were substituted for the armature. It is an essential advantage, however, that the system is arranged for free oscillation, i. e. that it does not abut against any unresilient stop or contact which would prevent the oscillation from being gradually built up to the desired maximum. For this reason the contact members 38 and 42 are formed by resilient blades.

In order to produce a sufficiently strong sound 35 the amplitude of the oscillating system must be comparatively large, about .15" for instance, in case of the afore-described diaphragm. On the other hand, the force with which the oscillating system resists its displacement must be high in order to attain a high frequency. In other words, the oscillating system must be rather stiff. Too strong a stiffness, however, has the disadvantage that it is difficult or even impossible to start the 45 oscillation and that it takes a relatively long time and a high power to reach the full amplitude and frequency.

I have solved the problem presenting itself herein by providing the weighted spring 33 so attached to the mass 28 and 24 as to freely oscillate perpendicularly to the diaphragm with a low frequency. In the initial stages of the starting period the spring 33 moves bodily together with the system of the armature 28 as hereinbefore stated. When the point of resonance is passed, however, the weight 34 is unable to follow the quick movements of the armature but tends to remain stationary, and this the more strongly the higher the frequency of the armature rises. The weighted end of the spring 33 finally remains nearly stationary so that the spring 33 exerts the same effect upon the armature as does the spring 30, i. e. it increases the stiffness of the oscillating system.

As this effect does not take place until a high frequency has already been reached it avoids the afore-mentioned disadvantages which would result from an invariable stiffness of the system. Consequently, a high trumpet-like tone can be obtained.

A particular advantage results from the coordination of the interrupter switch 40 with the oscillating system formed by the weighted spring 33. As the free end of the latter has a small amplitude, the contacts 40 are not opened until the

armature has nearly reached the upper end of its stroke. This results in a particular economical electric current consumption, which is still further decreased by the elastic suspension of the entire supporting structure for the electromagnet. This suspension renders the electromagnet capable of oscillating contrary to the oscillation of the armature. The relative movement between the armature and the electromagnet, however, counts for the intensity of the sound produced and this movement is the total of the individual oscillations of the armature and of the electromagnet.

In the embodiment shown in Fig. 7 similar reference numerals indicate corresponding parts. The diaphragm 130 is clamped between the flange 111 and the ring 113 and provided with an armature 128, the circuit of which is controlled by the interrupter—switch 140 diagrammatically indicated in the drawing. The armature 128 carries a spring blade 133 provided at its ends with weights 134. The latter are so dimensioned with respect to the spring 133 that the frequency of their natural oscillation is a small part of the frequency of the system formed by the diaphragm 130 with the mass 128. When referring to the frequency of the natural oscillation or, briefly, to the natural frequency of the system constituted by the diaphragm and the armature, or the weighted spring blade, respectively, I wish to 100 define the frequency with which either system would oscillate if it were disconnected from, or somehow freed from the influence of, the other system. Thus the natural frequency of the system 33, 34 would be obtained if the armature 28 were kept stationary and the weight 34 permitted of a free oscillation. Similarly, the natural frequency of the system 12, 28 would be obtained if the weighted spring 33 were cut off. Spring blades 145 serve to damp the oscillation of the 115 system with low frequency.

As the operation of this embodiment equals substantially that of the first described embodiment a detailed description thereof may be dispensed with herein.

The two end positions between which the spring blade 133 is oscillating during the normal operation are indicated in dotted lines clearly showing that the weights 134 remain nearly stationary whereby the stiffness of the oscillating system is increased to an extent necessary for producing a high trumpet-like sound.

What I claim is:

1. In an electric horn the combination comprising a diaphragm, an armature rigidly attached to the central part thereof to form therewith a main oscillating system, electromagnetic means to impart oscillations to said armature and diaphragm, a spring blade attached to and carried by said armature, a mass on the free end 135 of said spring blade constituting therewith an auxiliary oscillating system, the mass and the spring blade being so dimensioned that the natural frequency of said auxiliary system is materially lower than that of said main system, where- 140 by said spring will increase the effective stiffness of said main system at normal operation without increasing the stiffness at the initial actuation.

2. In an electric horn the combination com- 145 prising a diaphragm, an armature rigidly attached to the central part thereof to form therewith a main oscillating system, electromagnetic means to impart oscillations to said armature and diaphragm, a spring blade attached to and 150

carried by said armature, a mass on the free end of said spring blade constituting therewith an auxiliary oscillating system, the mass and the spring blade being so dimensioned that the natural frequency of said auxiliary system is materially lower than that of said main system, whereby by said spring will increase the effective stiffness of said main system at normal operation without increasing the stiffness at the initial actuation, and damping means coordinated with said spring blade to dampen the oscillation of said auxiliary system.

3. An electric horn comprising a diaphragm, a support therefor, an armature rigidly attached to the central part of the diaphragm to form therewith a main oscillating system, an electromagnet carried by said support to impart oscillations to said armature and diaphragm, a spring blade attached to and exclusively carried by said armature, a weight carried by said spring blade and forming therewith an auxiliary oscillating system, said weight being so dimensioned with regard to the spring blade that the natural frequency of said auxiliary system is materially lower than that of said main system, whereby said spring will increase the effective stiffness of said main system at normal operation without increasing the stiffness at the initial actuation.

4. An electric horn comprising a funnel, a diaphragm of spring sheet metal closing one end of said funnel, the interior of said funnel being unobstructed, an armature rigidly secured to the central part of said diaphragm forming with the latter a freely oscillating system, an electromagnet rigid with respect to said funnel for attracting said armature, an electric interrupter switch in circuit with said electromagnet, a spring blade connected with said armature in parallel relation to said diaphragm, said spring blade having its one end attached in fixed relation to said funnel and its other end freely projecting beyond said armature, a weight fastened to the free end of said spring blade, said weight being so dimensioned with respect to said freely projecting end that the frequency of its natural oscillation is substantially lower than that of said system whereby said spring will increase the effective stiffness of said main system at normal operation without increasing the stiffness at the initial actuation, the contacts of said switch being positioned for actuation by the movement of the spring blade.

5. The combination set forth in claim 7 provided with damping means coordinated with said spring to damp the oscillation thereof.

6. An electric horn comprising a funnel, a diaphragm of spring sheet metal completely closing the one end thereof, an armature rigidly secured

on the central part of said diaphragm forming with the latter a freely oscillating system, an electromagnet rigid with respect to said funnel for actuating said armature and diaphragm, a spring blade connected with said armature in parallel relation to said diaphragm, said spring blade having one end attached in fixed relation with respect to said funnel and its other end freely projecting beyond said armature, a mass fastened to said free end, the weight and position of said mass with respect to said freely projecting end being such that the frequency of its natural oscillation is substantially lower than that of said system whereby said spring will increase the effective stiffness of said main system at normal operation without increasing the stiffness at the initial actuation, two superimposed contact spring blades forming part of the circuit of said electromagnet and arranged between said diaphragm and said first mentioned spring blade, normally bearing against each other and against said spring blade and tending to separate when the latter is lifted, and an adjustable stop arranged to limit the movement of the lower contact-spring blade towards the upper contact-spring blade.

7. In an acoustic signal producer, the combination comprising an electric interrupter including an oscillatory armature and a contact cooperatively connected therewith, a diaphragm of spring sheet metal having a central portion directly carrying said armature and surrounded by a circular ridge and being so shaped in relaxed condition that a circumferential section along said ridge forms a wave-line, a support having an annular surface, means to press the marginal portion of said diaphragm against said surface to produce a tensional condition in said diaphragm which will increase the effective stiffness of the diaphragm at normal amplitudes of oscillation without increasing in proportion the stiffness at the amplitude requisite for the initial actuation of said contact, and an electromagnet secured to said support for imparting oscillations to said armature, the latter forming an oscillating system with said diaphragm, a floating weight, and a spring substantially parallel to the diaphragm and connecting said armature with said floating weight, whereby the weight may oscillate perpendicularly to said diaphragm, the said weight being so dimensioned with respect to said spring that its natural frequency of oscillation is considerably less than that of the oscillation of said system whereby said spring will increase the effective stiffness of said system at normal operation without increasing the stiffness at said initial actuation.

MAX GREINER.
